UNITED STATES PATENT OFFICE.

JOHN L. EVELAND, OF HORNELL, NEW YORK, ASSIGNOR OF ONE-HALF TO WILBER GATES, OF SOUTH DANSVILLE, NEW YORK.

WINDOW SHADE AND CURTAIN SUPPORT.

1,152,617.

Specification of Letters Patent.

Patented Sept. 7, 1915.

Application filed February 10, 1914. Serial No. 817,828.

To all whom it may concern:

Be it known that I, JOHN L. EVELAND, a citizen of the United States, residing at Hornell, in the county of Steuben and State of New York, have invented new and useful Improvements in Window Shade and Curtain Supports, of which the following is a specification.

This invention relates to a support for window shades and curtains and has for its object the production of a support for this purpose which can be readily and easily applied to various kinds and widths of window frames without injuring the same and still provide a reliable support for the window shade and curtain pole and which can be produced at comparatively low cost.

In the accompanying drawings: Figure 1 is a front elevation of a window shade and curtain support embodying one form of my invention and applied to a window frame. Fig. 2 is a top plan view thereof. Fig. 3 is a perspective view of one section of this support embodying my improvements. Fig. 4 is a horizontal longitudinal section of the same taken in line 4—4, Fig. 1 and looking upwardly. Figs. 5 and 6 are vertical transverse sections, on an enlarged scale, taken in the correspondingly numbered lines in Fig. 1. Fig. 7 is a front elevation showing a modified construction of my improvement applied to a window frame. Fig. 8 is a top plan view of the same. Fig. 9 is a vertical transverse section, on an enlarged scale, taken in line 9—9, Fig. 7.

Similar characters of reference indicate corresponding parts throughout the several views.

1, 1 represent the upright sides or stiles of the window frame which is usually mounted in the wall of the building so that the outer vertical edges 2, 2 of the stiles are exposed and therefore furnish places for the attachment of my improved shade and curtain support to the window frame.

3 represents the curtain pole and 4 the shade roller both of which may be of any suitable and well known construction.

In its general organization my improved window shade and curtain support, shown in Figs. 1—6, comprises two sections which are adapted to be mounted upon opposite sides of the window frame and support opposite ends of the curtain pole and shade roller. Each of these sections comprises a

body having an outer supporting head 5 which is adapted to be detachably mounted on the adjacent stile of the window frame, and an inner coupling arm 6 which is adapted to be adjustably connected with the corresponding arm of the other section in order to adapt the support to windows which vary in width. As shown in Figs. 1—6, the head of each supporting section comprises two parallel horizontal guide rods or bars 7, 7 arranged one above the other and connected at their inner ends by means of an upright tie rod or bar 8 while their outer ends are provided respectively with rearwardly and inwardly or reversely bent hooks 9 or spurs which are adapted to engage with the adjacent outer vertical edge of the companion stile of the window frame. The inner part or arm 6 of each supporting section is preferably constructed of sheet metal and secured at its outer end to the adjacent parts of the tie rod and longitudinal guide rods 7, 8 by providing this arm with sleeves 10, 11 which embrace the tie rod and the adjacent parts of the horizontal guide rods, as best shown in Figs. 1, 2, 3 and 4, thereby forming a firm and reliable connection between the head and arm of the body of each supporting section. The inner ends of the arms of both supporting sections may be adjustably connected in various ways, the means for this purpose shown in the drawings being satisfactory and consisting in overlapping the inner ends of these adjusting arms and embracing the same by means of a retaining loop 12 and providing a spring 13 which is connected at opposite ends with both arms so that the two bodies of the supporting sections are constantly drawn toward each other and the spurs thereof are held firmly in engagement with the vertical edges of the window frame and form a reliable support for the window shade and curtain roller. The spring 13 has its opposite ends adjustably connected with the arms in order to permit of adapting the same to windows varying in width and also to adjust the tension of this spring. The means which are shown in the drawings have been found suitable in practice and comprise coupling links 14 which are loosely secured to opposite ends of the spring 13 and adapted to be passed rearwardly through one of a horizontal row of openings 15 in one of the arms and engage its opposite ends with 110

5   sockets 16 formed on the rear side of these arms adjacent to opposite longitudinal edges of the respective opening. By this means the spring may be secured at its opposite ends to the arms at different points in the length of the latter for the purpose of adapting this spring to the position of the arms or windows of varying width and also enabling the proper tension of the spring to be obtained for reliably holding the spurs of the supporting body sections of the frame in engagement with the window frame.

10   17 represents two forwardly projecting brackets mounted on the two sections of the supporting bodies and adapted to support the curtain pole at opposite ends thereof. Each of these brackets is mounted on its companion supporting body so as to be capable of horizontal adjustment across the face of the window for adapting the same to the length of the pole of the style of the curtain which is to be draper on the same. The preferred means for effecting this adjustment comprises an upright channel-shaped 15 adjusting yoke 18 which has its concave side facing rearwardly and provided in its rearwardly projecting flanges with upper and lower pairs of openings which receive the upper and lower guide rods or bars 7 on the 20 respective supporting body. The curtain bracket is preferably formed in one piece with one of the flanges of this adjusting yoke and projects upwardly and forwardly therefrom.

25   20 presents an upright supporting plate arranged in rear of the guide rods and provided at its inner and outer edges with forwardly projecting guide flanges 21, 22 each of which is provided with openings which 30 receive the guide rods. The outer guide flange 22 is arranged between the rearwardly projecting flanges of the adjusting yoke so that upon shifting the supporting plate 20 horizontally inwardly or outwardly the bracket supporting yoke 18 will be compelled to move with the same.

35   23 represent forwardly projecting brackets which support opposite ends of the shade roller and which are mounted on the two 40 body sections of the support so as to be capable of horizontal adjustment across the face of the window for adapting the position of these brackets to suit the length of the shade roller. Each of these shade roller brackets 45 is preferably formed on a flange 24 projecting forwardly from the inner end of a horizontally adjustable supporting plate 25 arranged between the rear side of the guide rods and the front side of the curtain 50 bracket supporting plate, said shade roller supporting plate being also provided at its outer end with forwardly projecting flanges.

55   26. The last mentioned flanges and the inner flange of the shade roller supporting 55 plate are provided with openings which re-

ceive the upper and lower guide rods. By sliding the front plate lengthwise on the guide rods the bracket 23 may be adjusted to suit the position of the adjacent end of the shade roller and the companion curtain pole bracket 17 may likewise be adjusted lengthwise into the desired position for properly receiving the curtain pole by sliding the rear plate lengthwise on the guide rods. After these two plates and the parts associated therewith have been shifted into the desired position the same are clamped in place on these guide rods by applying a lateral pressure against these plates. This is best effected by a single clamping device which preferably consists of a clamping screw 27 working in a threaded opening in the front supporting plate and engaging with the front side of the rear supporting plate and provided with a fingerpiece or handle 28 at its front end. Upon tightening this screw so as to press against the rear plate the latter will be pressed rearwardly and the front plate will be pressed forwardly, thereby causing the flanges of these plates to press in opposite directions against the horizontal guide rods and grip the same sufficiently tight to hold the companion brackets against displacement.

These means of adapting the curtain and shade support to windows of varying width and also to shade rollers and curtain poles which vary in length are comparatively simple in construction and can be produced at comparatively low cost. Moreover they can be easily manipulated and conveniently applied to the windows, curtain poles and shade rollers and after the same are installed they do not detract from the neat appearance of the window.

In the modified construction of my improved window shade and curtain support or holder the head 29 and the arm 30 of each supporting body is stamped out of one piece of sheet metal and the outer edge of the head is turned rearwardly and provided with spurs or hooks 31 which engage with the vertical edge of the adjacent stile of the window frame. The spurs of both body sections are held in engagement with the opposite stiles of the window frame by means of a spring 32 which is connected at opposite ends with the arms of both supporting bodies. This connection between the spring 32 and the arms is effected by substantially the same means which have been described with reference to the construction shown in Figs. 1-6 and enables the connection between this spring and each supporting arm to be shifted to suit the width of the window to which the support is applied and also to vary the tension of the spring as may be required. The curtain pole 3 in this case is supported on the front ends of brackets 33 each of which is pro-

- vided at its rear end with a depending shank 40 which engages with a socket 34 preferably formed by stamping a portion of the companion head 29 forwardly therefrom.
- 5 The shade roller 4 is supported at its opposite ends on brackets 35 each of which is mounted on a sliding plate 36 which is movable horizontally on the front side of the companion head 29 for adapting the last mentioned bracket to the length of the shade roller. The means shown in Figs. 7, 8 and 9 for guiding the sliding plate 36 on the head consist of upper and lower rows of guide lugs 37, 38 stamped bodily out of the head 15 to form two guideways which receive the upper and lower edges of the sliding plate. After the latter has been shifted to the desired position the same is held in place by means of a clamping or set screw 39 engaging with a threaded opening in the sliding plate and bearing at its rear end against the front side of the head 29, as shown in Fig. 9.
- In both of the constructions herein shown 25 and described the supporting bodies of the two main sections are drawn against opposite edges of the window frame and held in reliable engagement therewith by a single spring and the latter is capable of adjustment relative to these supporting bodies to enable the fixture to be adapted to windows varying in width and also to adjust the tension of the spring to suit different conditions.
- 35 I claim as my invention:
1. A window shade and curtain support, comprising two body sections each of which is provided at its outer end with spurs adapted to engage with the outer edge of a 40 window frame and at its inner end with an arm which slides past the corresponding arm of the other section, a loop embracing both arms, and a spring connecting said arms.
- 45 2. A window shade and curtain support, comprising two body sections each of which is provided at its outer end with spurs adapted to engage with the outer edge of a window frame and at its inner end with an 50 arm which is provided with a plurality of
- openings arranged in a horizontal row, and a spring provided at each end with a coupling link adapted to pass through one or another opening of one of said arms and against the rear side of said arm adjacent to opposite edges of the respective opening.
3. A window shade and curtain support, comprising two body sections each of which has a head composed of two horizontal rods, hooks arranged at the outer ends of said rods and adapted to engage with the outer edge of a window frame, a vertical rod connecting the inner ends of said horizontal rods, and an arm connected with the inner part of said head, and a spring connecting said arms.
4. A window shade and curtain support, comprising two body sections each of which has a pair of horizontal parallel guide rods, a supporting plate provided with perforated flanges which receive said rods and a channel-shaped yoke which receives one of said flanges and is guided on said rods and is provided with a bracket.
5. A window shade and curtain support, comprising two body sections each of which has a pair of horizontal parallel guide rods, two supporting plates arranged side by side and guided on said rods and each provided with a bracket, and means for pressing said plates laterally relatively to each other for clamping the same on said rods.
6. A window shade and curtain support, comprising two body sections each of which has a pair of horizontal parallel guide rods, two supporting plates arranged side by side and guided on said rods and each provided with a bracket, and means for pressing said plates laterally relatively to each other for clamping the same on said rods, comprising a clamping screw arranged in a threaded opening in one of said plates and engaging with the other plate.

Witness my hand this 31st day of January, 1914.

JOHN L. EVELAND.
